(57) **CLAIM**

The ornamental design for a case for electronic devices, as shown and described.

DESCRIPTION

FIG. 1 is a front perspective view of a case for electronic devices, comprised of an inner shell, upper outer frame, and lower outer frame, showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is an enlarged top plan view thereof;

FIG. 8 is an enlarged bottom plan view thereof;

FIG. 9 is a front perspective view of the inner shell, shown isolated from the case for electronic devices for clarity;

FIG. 10 is a rear perspective view of the inner shell, shown isolated from the case for electronic devices for clarity;

FIG. 11 is a front perspective view of the upper outer frame, shown isolated from the case for electronic devices for clarity;

FIG. 12 is a rear perspective view of the upper outer frame, shown isolated from the case for electronic devices for clarity;

FIG. 13 is a front perspective view of the lower outer frame, shown isolated from the case for electronic devices for clarity;

FIG. 14 is a rear perspective view of the lower outer, shown isolated from the case for electronic devices for clarity;

FIG. 15 is a front exploded perspective view of the case for electronic devices; and,

FIG. 16 is a rear exploded perspective view of the case for electronic devices.

Although the case for electronic devices in which the claimed design is embodied consists of an inner shell, upper outer frame, and lower outer frame, the claim is directed to the ornamental appearance of the case for electronic devices in its entirety and does not extend to the ornamental appearance of each of the individual components in isolation. The broken lines depict portions of the case for electronic devices that form no part of the claimed design.
